UNITED STATES PATENT OFFICE.

HEINRICH KOEPP, OF MILWAUKEE, WISCONSIN, ASSIGNOR TO KATHARINA ROSA, OF SAME PLACE.

SAD-IRON.

SPECIFICATION forming part of Letters Patent No. 445,184, dated January 27, 1891.

Application filed June 10, 1889. Serial No. 313,653. (No model.)

To all whom it may concern:

Be it known that I, HEINRICH KOEPP, of Milwaukee, in the county of Milwaukee and State of Wisconsin, have invented certain new and useful Improvements in Sad-Irons; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

My invention relates to hollow or chambered sad-irons. Its main object is to secure a more perfect distribution and regulation of the draft; and it consists, essentially, of certain peculiarities of construction and arrangement, hereinafter particularly described, and pointed out in the claims.

In the accompanying drawings like letters designate the same parts in the several figures.

Figure 1 is a perspective view of my improved sad-iron. Fig. 2 is a plan view of the same with the lid or cover partially open and the handle removed. Fig. 3 is a medial longitudinally vertical section of the iron, and Fig. 4 is a vertical cross-section of the same.

F represents the body of the sad-iron formed in the usual manner with an interior fire box or chamber for the reception of the fuel by which the iron is heated. It is provided in each side near the bottom with draft-openings, preferably in the shape of round perforations $a a$, arranged up and down in oblique or inclined lines. It is also provided in each of the inclined walls forming the point of the iron with like draft-openings or perforations $a' a'$ similarly arranged.

B is the cover or lid, of the usual form and construction, provided with a handle C of suitable form and material. It is pivoted to the rear end of the body A of the iron by means of a pin or screw b , so as to swing in opening or closing horizontally to either side. In a post a^2 formed at the apex of the iron is pivoted a gravitating latch E, and on the upper side of the lid, near its apex, are formed one or more vertical flanges $e e$, notched at

the center so as to receive and engage the gravitating latch E, and inclined or beveled from the notches at the center toward the opposite edges of the cover, so as to pass in closing the lid in either direction underneath the latch and automatically raise the same over the higher portions of said flanges adjacent to the notches therein. By thus arranging the lid to swing horizontally in opening and closing and by attaching the handle of the iron to said lid the liability is avoided of accidentally upsetting the iron and spilling its contents by grasping the handle and lifting it when the lid is unfastened. At the same time the handle serves as a convenient and ever-present means of manipulating the lid when it is hot. The manner of hinging the latch E to the iron and the formation of the notch or recess in the cover with which the latch is to engage may be variously modified.

F F are dampers, consisting each of a side plate perforated to correspond with the perforations $a a$ in the sides of the iron, to the inner sides of which they are held by means of rivets or screws $f f$, secured in the upper portion of each damper and projecting through horizontal slots in the adjacent walls of the iron, as clearly shown in Figs. 1 and 4, and of a plate F', hinged to the front end of said side plate, as shown in Figs. 2 and 3, so as to shut snugly against the inner side of the adjacent inclined wall when the damper is closed. These damper-plates are provided with perforations corresponding with those in the adjacent walls of the iron and with inclined or oblique inwardly-projecting wings $f' f'$, located between the oblique rows of perforations and similar but thinner inclined wings $f^2 f^2$, extending midway across said perforations, as shown in Fig. 3. These inclined wings not only serve to hold the fuel away from the openings and thereby afford a freer and more certain draft, but they serve also to conduct the ashes dropping thereon along their upper inclined faces past the openings to the bottom of the iron, and thereby prevent their escaping through the draft-openings and smutting the work. The hinged plates F' F' are guided and held in place

relatively to the adjacent sides of the iron by studs f^3 f^8 , projecting upwardly from the bottom of the iron.

By constructing the iron, as hereinbefore described, with perforations in the inclined walls forming the point or apex and providing the damper with the hinged plates F' , the draft is more perfectly regulated and controlled, inasmuch as without the perforations or draft-openings in the inclined walls at the front end of the iron the fuel in that portion of the iron would not burn as rapidly, and consequently that part of the iron would not be heated to the same degree as the rest of the iron, and if such draft-openings were provided with no means of closing the same the point of the iron would be liable to become overheated.

Upon the screws or pins f f outside of the iron are pivoted gravitating plates GG , formed with horizontal slots g , in the extremities of which are upward offsets adapted to engage with pins g' , projecting from the sides of the iron, so as to hold the dampers either open or closed, thereby preventing their displacement by any movement of the iron incident to its operation. I provide these plates G at their free ends with outwardly-projecting thumb-pieces g^2 , as shown in Figs. 1 and 2, to facilitate the shifting of the dampers. The iron is provided at the bottom of the rear end in the usual manner with an opening and door D for the purpose of removing the ashes therefrom. The bottom is also extended at the rear end beyond said opening and formed with an upturned flange d to prevent the ashes escaping from the adjacent opening from falling upon the work.

I do not claim, broadly, as my invention a hollow sad-iron having its sides provided with draft-openings in combination with dampers for the openings having a series of inwardly-extending ribs.

I claim—

1. The combination, with a chambered sad-iron the sides of which are bent toward each other to form the point and are provided with draft-openings both in front of and behind the bends therein, of dampers composed of sections jointed together adjacent to the bends in the sides of the iron and movable lengthwise thereof so as to open and close said openings, substantially as and for the purposes set forth.

2. The combination, in a chambered sad-iron having draft-openings in the sides, of dampers having corresponding openings and inwardly-projecting wings across said openings, substantially as and for the purposes set forth.

3. The combination, in a chambered sad-iron, of draft-openings formed in the sides thereof, and horizontally-movable dampers provided with corresponding openings and with inwardly-projecting inclined wings located between the rows of openings therein and similar wings extending midway across said openings, substantially as and for the purposes set forth.

In testimony that I claim the foregoing as my own I affix my signature in presence of two witnesses.

HEINRICH KOEPP.
